UNITED STATES PATENT OFFICE.

SYLVANUS C. HOPKINS, OF BOSTON, MASSACHUSETTS.

FOLDING TABLE.

SPECIFICATION forming part of Letters Patent No. 336,717, dated February 23, 1886.

Application filed August 25, 1884.

To all whom it may concern:

Be it known that I, SYLVANUS C. HOPKINS, of Boston, Massachusetts, have invented certain Improvements in Folding Tables; and I hereby declare that the same are fully described in the following specification and illustrated in the accompanying drawings.

My improvements relate to that class of folding tables having crossing pivoted legs and a hinged top adapted to fold downwardly, so as to protect the finished upper surfaces and make a compact package.

My invention consists in the devices and combinations of devices set forth in the appended claims.

In the drawings, Figure 1 is a vertical central section of the spread table, taken at right angles to the plane of folding; Fig. 2, an end view of the folded table, and Fig. 3 a side elevation. Fig. 4 is a plan of the under side of the table-top with the legs removed, while Figs. 5 and 6 show details of the invention.

A A' are respectively the upper and lower sections of one pair of legs, and B B' the corresponding parts of the other pair.

C C' represent connecting-knees, which join the upper and lower parts of each leg, that they may act as one.

The drawings represent the upper and lower sections united by diagonal bars securely fastened to the parts A and A' or B and B'. If made as thick as the two sections of the table-top combined, these bars C C' may be straight pieces or blocks, at the opposite ends and to the opposite sides of which the parts of the leg are made fast.

D is the pivot by which the connecting-bars of the crossing legs are united to fold and unfold, and E E' are cross-pieces secured to the legs, by which the ends of the knees C C' may be held in place and concealed. The knees may, if preferred, be secured to these cross-pieces rather than directly to the legs.

With the construction shown in the drawings the knees C C' may abut at the point c against the edge of the piece E, (see Fig. 1,) and form a stop to check the movement at the proper point. In like manner the shoulders a b' of the opposite leg-frames may abut for the same purpose. An advantage of this construction and connection of the parts of the legs is the increased symmetry of the table

due to the fact that the corresponding upper and opposite sections of the legs may be uniform in contour and in precisely the same 55 planes, transverse to the folding axes or at right angles to the plane of folding of the table. The same is true of the lower sections of the legs, which are or may be identical in outline one with another, and hence a much 60 more graceful structure is produced than would result if the legs were continuous, crossing each other side by side and not in the same transverse plane. Another advantage is that the legs recede from each corner toward a point beneath the center of the table, and consequently do not obstruct the movement of persons sitting around it, as in tables having legs vertical or in vertical planes.

This device admits of great strength, and the arrangement allows a close resemblance to the well-known "cluster-leg" center-table. The table-top is formed in two sections, F F', connected together at the top and center by the hinges G G'. A rail, H, is secured to the underside 70 of the table-top, extending along the sides or along the sides and ends. To this rail the upper ends of the legs are attached by hinges I I'. The top F F' may therefore fold downwardly between the parts A B of the legs by 75 means of the hinges G G' and I I' and the pivots D D', and in so folding the structure is brought into the most compact form, the upper surfaces of the table mutually protecting each other and the legs closing into parallel 80 planes, separated only by the thickness of the parts F and F'. (See Fig. 2.)

The advantage of employing the rail H and hinging to its lower inner corner the upper outer corner of the leg-frames is obvious from 90 Fig. 2, where the folding of these particular parts is shown to be as compact as though the inner upper corner of the leg-frame was hinged to the under side of the table direct, and from Fig. 1, where it is obvious the arrangement adds the thickness of the rail H to the height of the spread table as it would otherwise be. In other words, with a given height of table greater compactness is attained 95 in the manner stated.

To maintain the table-top F F' in proper horizontal position when spread, I provide at each end a spring-latch, K, secured to one of the abutting ends of the rail H and engaging

automatically with a stud, K', on the opposite end, from which it may be detached by pressure on the projecting thumb-piece.

Another feature of my invention is the surface-dowel L L', Figs. 4 and 6, secured beneath the center of the table-top at the line of folding and employed to retain the parts F F' in proper relative position vertically and longitudinally. It is a fixed metallic surface-bolt and socket engaging when the sections of the table-top come together and disengaging when said sections separate. The best form in which I have embodied it is shown in the drawings. The part L of the dowel has a projecting tongue with a depressed surface each side of it, and the part L' has a recess to receive said tongue, flanked by raised projecting surfaces. These peculiarities of form permit the parts L and L' to interlock; and when the table is opened or spread for use they engage and mutually support the edges of the table-leaves F and F', so that independent vertical or longitudinal movement is prevented.

I claim as my invention—

- 25 1. As a new article of manufacture, a folding table having its top made in two parts hinged centrally, so as to drop downward between the tops of the legs in folding, and its four pivoted legs converging from the corners 30 toward a central point and diverging therefrom, substantially as shown and described.
2. A table having a top made in two parts and adapted to fold centrally downward between crossing permanently pivoted legs, 35 which all converge toward a point beneath the center of the table, for the purpose set forth.
3. In a folding table, the combination of a hinged and folding top with crossing pivoted

legs formed each in two sections fastened to a central hinge-bar on opposite sides thereof, 40 so as to bring the upper and lower sections of each leg into different planes, and leave a space between them equal to twice the thickness of the hinged top, into which space the two hinged sections of the table-top fold, substantially as 45 set forth.

4. In a folding table, the centrally-hinged top having marginal rails H H, secured to its under surfaces in lines parallel to the axis of folding, in combination with crossing pivoted 50 legs hinged at their extreme upper outer corners to the lower inner corners of the rail, whereby increased height of the spread table or greater compactness of the folded structure is attained, substantially as set forth. 55

5. In a folding table, the combination of the hinged top, formed in two parts, F F', the pivoted legs A A' B B', and the connecting-knees C C', with the cross-pieces E E', substantially 60 as and for the purpose set forth.

6. The combination of crossing pivoted legs and top folding between them with an automatic spring lock or catch, adapted to secure the table-top in its spread position and give horizontal support to its parts, substantially 65 as set forth.

7. A metallic surface dowel formed in two parts, as described, adapted to interlock and to each bear upon the other both vertically and laterally, so as to support the abutting 70 edges of the table-top, substantially as set forth.

SYLVANUS C. HOPKINS.
